Primary Examiner — Keli L Hill*Assistant Examiner* — Sara S Sahneh(74) *Attorney, Agent, or Firm* — Sean R. Wilsusen, Esq.; Carter, DeLuca & Farrell LLP(57) **CLAIM**

The ornamental design for a locking boot for vehicle wheel, as shown and described.

DESCRIPTION

FIG. 1 is top perspective view of a locking boot for vehicle wheel;

FIG. 2 is a bottom perspective view thereof;

FIG. 3 is a top plan view thereof;

FIG. 4 is a bottom plan view thereof;

FIG. 5 is a first side view thereof;

FIG. 6 is a second side view thereof;

FIG. 7 is front view thereof; and,

FIG. 8 is rear view thereof.
